FLANGE OILER

Frank Ross, Frank E. Ross, Jr., and
Harley G. Field, St. Louis, Mo.

Application July 19, 1948, Serial No. 39,414

4 Claims. (Cl. 184—3)

1

This invention appertains to lubricating devices and more particularly to a novel oiler for the flanges of car wheels.

One of the primary objects of this invention is to provide a flange oiler which will operate to deliver oil only as long as the car is in motion, thereby preventing the delivery of oil to the flanges when the car is standing still and thus preventing the wastage of oil and the danger of oil dripping on the treads of the wheel and other undesired places.

Another salient object of the invention is to provide means for automatically supplying a measured quantity of oil to the flanges only of the wheels and thereby effectively eliminate the setting of hand valves and the like commonly employed in gravity oilers.

A further object of the invention is the provision of a novel brush plate for engaging directly against the wearing side of the flange of a car wheel with novel means for supplying oil to the plate when the car is in motion, the brush plate functioning to wipe oil on the flange and to keep the flange clean, any dirt collecting on the operative face of the plate acts to retain oil and to facilitate the desired placing of an oil film on the flange.

A further important object of the invention is the provision of novel means for mounting the brush plate in position, whereby the brush plate will be effectively held against the flange irrespective of lateral or other movement of the wheels, the mounting also permitting the swinging of the brush plate and its associate parts to an out of the way position, when repairs or replacements to the wheels' brake shoes become necessary.

A still further object of this invention is to provide a flange lubricator which will operate successfully under all weather and dirt conditions and one which will be economical in use and which can be easily applied to existing car trucks without change thereto.

With these and other objects in view, the invention consists in the novel construction, arrangement and formation of parts as will be hereinafter more specifically described and claimed and illustrated in the accompanying drawings, in which drawings,

Figure 1 is a fragmentary, side elevational view of a railroad locomotive or car illustrating one truck thereof and showing our novel flange lubricator operatively connected therewith.

Figure 2 is an enlarged detail vertical sectional view through the oil reservoir and one

2

pump, the section being taken substantially on the line 2—2 of Figure 3 looking in the direction of the arrows, the view also showing the novel means employed for operating the pump.

5 Figure 3 is a fragmentary, horizontal, sectional view taken substantially on the line 3—3 of Figure 2, looking in the direction of the arrows.

Figure 4 is a transverse, sectional view through the reservoir and pumps, the section being taken 10 substantially on the line 4—4 of Figure 2, looking in the direction of the arrows, the view being taken on a still greater scale than Figures 2 and 3.

Figure 5 is a substantially horizontal, sectional view taken on the line 5—5 of Figure 6, looking 15 in the direction of the arrows illustrating the novel mounting for the brush plate.

Figure 6 is a detail, vertical, sectional view 20 taken on line 6—6 of Figure 5 looking in the direction of the arrows and showing the novel mounting of the brush plate.

Figure 7 is a fragmentary, transverse sectional view taken on the line 7—7 of Figure 6, looking 25 in the direction of the arrows, Figures 5, 6 and 7 being on the same scale as Figure 4.

25 Referring to the drawings in detail, wherein similar reference characters designate corresponding parts throughout the several views the letter O generally indicates our novel flange oiler for a locomotive L or other piece of railroad rolling stock.

The locomotive L or other piece of railroad rolling stock will not be described in detail and it is sufficient to note that the same includes the usual truck 10, having journal boxes 11 for the 30 axles of the car wheels 12. The car wheels 12 are of the ordinary type and include the tread 13 and the flange 14.

The novel oiler includes an oil reservoir or 35 tank 15 made from the desired material and of a size and shape best suited for the purpose intended and to contain a certain quantity of oil. As illustrated, the reservoir 15 includes a body portion 16 having a bottom wall 17 and side and end walls 18. A removable cover 19 is provided.

40 The cover can be held down by machine screws 20 and a gasket 21 can be employed for preventing the escape of oil from the reservoir and the entrance of dirt into the reservoir. The bottom wall 17 is preferably inclined downwardly toward one point to form a water collecting sump. A drain plug 22 can be provided at that point. The 45 cover is provided with a filling cap 23, and a filtering screen 24 can be carried by the cover directly inward of the filling cap.

50 The reservoir forms a housing for a pair of

pumps 25 and 26. One pump is utilized for the front wheels 12 of the truck 10 and the other pump 26 is utilized for the rear pair of wheels 12 of the truck. These pumps are identical in construction and operation and are operated synchronically by the movement of the sprung and unsprung parts of the truck 10. At this point, it is to be noted that the bottom wall 17 of the reservoir 15 is provided with a transversely extending bearing boss 27. This bearing boss receives a supporting pivot bolt 28, which is rigidly carried by a sprung part of the truck. A wear or bearing sleeve 29 can be placed around the pivot bolt 28. The pumps 25 and 26 are operatively connected to an unsprung part of the truck.

The pumps 25 and 26 will now be described in detail.

Each pump includes a barrel 30 carrying at its lower end a pump cylinder 31. The cylinder is closed by a cylinder head 32 threaded on the lower end of the barrel. The cylinder head 32 is provided with an intake port 33 normally closed by a ball check valve 34. The upper end of the barrel 30 carries a packing nut 35 through which is slidably mounted for reciprocative motion the hollow pump plunger 36. The lower end of the hollow pump plunger carries a plunger head 37 having a packing ring for close engagement with the inner wall of the pump cylinder 31. The plunger head 37 is provided with an axial passageway 38, which is normally closed by a ball check valve 39. The pump plunger 36 is also provided with a stop collar 40 and an expansion spring 41 bears against this collar and against the packing nut 35. Hence the spring functions to normally urge the pump plunger to a lowered position. The extreme upper end of the pump plunger has threaded thereon a nipple 42 and this nipple forms a cage for retaining a spring press ball check valve, 43 in position against the upper end of the hollow plunger rod.

The plunger rods 36 of the pumps 25 and 26 are connected together by a cross head 44. The cross head 44 has rockably mounted thereon a bearing collar 45, which forms a part of the operating mechanism for the pumps. This collar is connected to an operating lever 46. The lever 46 is of the telescoping type and thus includes a cylindrical main portion 47 and a solid portion 48 which is rigidly secured to the collar 45. The outer end of the tubular portion 47 of the lever 46 is pivotally connected by means of a pivot stud 49 to a bracket 50. The bracket 50 is welded or otherwise rigidly secured to the unsprung portion of the truck, such as the journal boxes 11.

An adjustable fulcrum 51 is provided for the lever 46, so as to regulate the stroke of the pump plungers. The adjustable fulcrum 51 includes a bracket plate 52 having pivot ears 53 formed on the opposite sides thereof. A yoke 54 straddles the bracket plate and is connected, by means of pivot pins 55 with the pivot ears 53. The central portion of the yoke is rigidly connected to the cylindrical main or tubular portion 47 of the lever. Rigidly fastened to the cover plate 19 is a stud 56. This stud extends through a longitudinally extending slot 57 formed in the bracket plate 52. The opposite ends of the bracket plate carry stop pins 58 for engaging against the stud and the upper end of the stud carries a lock nut 59 which can be threaded down tight against the bracket plate. Adjustment of the bracket plate on the stud bolt can be had by loosening the nut 59 and then adjusting the stop pins 58. Ob-

viously, by moving the bracket back and forth the active stroke of the plungers for the pumps can be regulated.

From the description so far, it can be seen that when the car or locomotive L is in transit and motion occurs between the sprung and unsprung parts of the truck, that the lever 46 will be actuated causing a reciprocatory movement of the pump plungers 36. Considering that the reservoir 15 is filled with oil, it can be seen that upon the up stroke of the plungers the balls 39 and 43 will be held upon their seats, but that the ball check valves 34 will be lifted up by the suction and oil will be taken into the pump cylinders. Upon downward movement of the pump plungers the ball check valves 34 will be forced down on their seats by pressure and the ball check valves 39 will be lifted off their seats by the incoming oil. When the pump plungers are filled with oil the ball check valve 43 will also be moved off of their seats by the pressure of the oil upon the down stroke of the plungers and this oil will then be forced out of the pump plungers and through the nipples. The main function of the ball check valves 39 is to prevent the draining of oil out of the pump plungers and to aid in the elevation or forcing of the oil out of the upper ends of the plungers. The movement of the plungers is slight and in actual practice a small given quantity of oil will be forced out of the reservoir upon each movement of the plungers.

One of the main features of the invention is the provision of novel means for wiping the oil delivered from the plungers to the flanges 14 of the car wheels 12. As heretofore brought out the pump 25 is utilized for forcing the oil to the oil applicator for the front wheels 12 of the car, and the pump 26 is utilized for supplying oil to the oil applicator for the rear wheels. These oil applicators are indicated respectively by the numerals 60 and 61. Each of these oil applicators are identically the same in construction and it is to be noted that flexible hoses 62 and 63 lead respectively to oil applicators 60 and 61. The hose 62 leads directly to its applicator, while the hose 63 is connected to a delivery pipe 64 which extends along the truck back toward the oil applicator 61 and the pipe 64 is in turn connected by a flexible hose 65 to the applicator 61.

Each applicator includes a hanger bracket 66 which is welded or otherwise rigidly secured to a convenient part of the truck 10. This bracket carries a pivot stud bolt 67 on which is rockably mounted, by means of suitable bearings 68 the supporting lever 69. This lever 69 extends toward and over the adjacent wheel. Slidably mounted in the outer end of the lever 69 is a supporting sleeve 70. As is clearly shown in Figure 5, this sleeve extends laterally of the lever toward the flange of the wheel. Secured to the sleeve 70 on one side of the lever 69 is a stop washer 71 and detachably secured to the sleeve on the opposite side of the lever is a similar stop washer 72. A relatively short spring 73 is coiled about the sleeve 70 and abuts against the stop washer 72 and the lever 69 and normally urges the sleeve toward the flange of the wheels. The purpose of this arrangement is to obtain flexible support for sleeve 70 and yet retain a self-squaring force tending to hold sleeve 70 in a line perpendicular to side of lever 69. Slidably mounted in the sleeve 70 is an oil delivery tube 74. This tube has connected therewith by means of nipples and suitable couplings 75, the flexible hose. The hose 62 leading 75 from the pump 25 is connected by the nipples

and couplings to its oil applicator 60 and the hose 65 is connected by the nipples and couplings to its oil applicator 61. The inner end of the oil supply tube 74 carries the brush plate 76. This brush plate is preferably formed from metal. As is also best shown in Figure 5 the brush plate 76 is provided with an opening 77 and the tube 74 extends into this opening and is connected to the wall thereof. Hence oil delivered to the tube will flow into this opening 77 and to the inner face of the brush plate. An expansion spring 78 is coiled about the tube 74 and bears against the outer face of the brush plate and the stop washer 72, consequently, the brush plate will normally be urged outwardly and into wiping engagement with the flange 14 of its car wheel.

It can be seen that the brush plate 76 is mounted for movement so that the same can swing up and down and transversely of the lever 69. Thus the brush plate can follow the various movements of the car wheel.

Much stress is laid on the point of brushing contact with the wearing face of the wheel flange and the plate 76. This contact is such that the oil is only supplied to the flange and the oil is wiped on the flange during the rotation of the wheel. As the supply of oil is governed by the stroke of the oil supply pump only a limited quantity of oil is delivered to a brush plate. Consequently, an excess of oil delivery to a brush plate is prevented and only sufficient oil is supplied to the flange to lubricate the same. Consequently, the oil will not flow or drip onto the wheel tread or the rails of the track. Each brush plate functions to wipe and clean the car flange and any dirt collecting on the active face of a brush plate will act as a sponge to collect and hold the oil. As soon as the car or locomotive stops further delivery of oil is stopped, and consequently wastage is eliminated and oil will not drip down on the car wheels while the train is standing still.

Another important feature, is that the mounting of the brush plate is such that the same can be swung to a raised inoperative position (see dotted lines showing in Figure 1). This permits free access to be had to the brake shoes.

From the foregoing description it can be seen that we have provided an efficient and durable flange oiler, which is so constructed as to operate under all weather conditions.

While we have shown the lubricator on sprung and unsprung parts of the truck, it is to be understood that the same could be mounted on two sprung parts of the truck or in fact at any point where relative motion is had between parts of the truck.

Changes in details may be made without departing from the spirit or the scope of this invention, but what we claim as new is:

1. In a flange oiler for car wheels, an oil reservoir, means rockably connecting the oil reservoir to a sprung part of a car truck, a pump in said reservoir including a cylinder, a pump plunger reciprocally mounted in the cylinder, said plunger

extending exteriorly of the reservoir, a lever fulcrum on said reservoir, a lever rockably mounted on the fulcrum, means rockably connecting the lever to the pump plunger, and means rockably connecting the outer end of the lever to the unsprung part of a car truck.

2. In a flange oiler for car wheels, an oil reservoir, means rockably connecting the oil reservoir to a sprung part of a car truck, a pump in said reservoir including a cylinder, a pump plunger reciprocally mounted in the cylinder, said plunger extending exteriorly of the reservoir, a lever fulcrum on said reservoir, a lever rockably mounted on the fulcrum, means rockably connecting the lever to the pump plunger, and means rockably connecting the outer end of the lever to the unsprung part of a car truck, said lever including sliding sections.

3. In a flange oiler for car wheels, an oil reservoir, means rockably connecting the oil reservoir to a sprung part of a car truck, a pump in said reservoir including a cylinder, a pump plunger reciprocally mounted in the cylinder, said plunger extending exteriorly of the reservoir, a lever fulcrum on said reservoir, a lever rockably mounted on the fulcrum, means rockably connecting the lever to the pump plunger, means rockably connecting the outer end of the lever to the unsprung part of a car truck, said pump plunger being hollow and provided with ball check valves, an inlet valve for the lower end of the cylinder, and an outlet nipple carried by the outer end of the pump plunger.

4. In a flange oiler for car wheels, an oil reservoir, means rockably connecting the oil reservoir to a sprung part of a car truck, a pump in said reservoir including a cylinder, a pump plunger reciprocally mounted in the cylinder, said plunger extending exteriorly of the reservoir, a lever fulcrum on said reservoir, a lever rockably mounted on the fulcrum, means rockably connecting the lever to the pump plunger, and means rockably connecting the outer end of the lever to the unsprung part of the car truck, said fulcrum being mounted for movement toward and away from the connection of the lever with the pump plunger.

FRANK ROSS.
